UNITED STATES PATENT OFFICE

PHILLIPS THOMAS, OF EDGEWOOD, PENNSYLVANIA, ASSIGNOR TO WESTINGHOUSE ELECTRIC & MANUFACTURING COMPANY, A CORPORATION OF PENNSYLVANIA

COMPENSATED PARALLELING SYSTEM

Application filed September 19, 1927. Serial No. 220,556.

This invention relates broadly to an instantaneous paralleling relay system having completed voltage compensation.

The principal object of this invention is to provide means for paralleling parts of the same alternating-current distribution system and also to provide a scheme that may serve as a phase-unbalance relay.

A further object of this relay scheme is to provide a system by which paralleling of two branches of the same alternating-current distribution system shall be effected whenever the voltages of the two branches are of normal value and in phase.

15 A further object of this relay system is to provide for the paralleling of the two branches of a distribution system upon phase coincidence of the voltages of the branches, if the voltage of one branch is normal and the 20 voltage of the other branch below normal or if both are below normal, whether equal or not.

Another object of this invention is to prevent paralleling of two branches of an alternating-current system even if the voltages thereof are in phase if the voltage of one is normal and that of the other above normal, or if both voltages are above normal, whether equal or not.

30 Another object is to provide a relay system which shall prevent paralleling of two alternating-current circuits when the phase voltages of one circuit assume unsymmetrical phase positions.

35 The relay system which I have devised to accomplish the above objects is shown diagrammatically in the single figure of the accompanying drawing.

In the drawing I have indicated two 40 branches of an alternating-current distribution system at 1—2 and 3—4, or lines 1, 2 and 3, 4 may be low tension leads from potential transformers connected to the two branches. The conductors 1 and 3 are connected by the 45 conductor 5. Across the two branches are connected the transformers 6 and 8, respectively, while transformer 7 is connected, through transformers 6 and 8, to the lines 2 and 4 of the two branches. This scheme of 50 connections causes the resultant of the volt-

ages of the two branches 1—2 and 3—4 to be impressed upon the primary of the transformer 7.

The transformers 6, 7 and 8 supply alternating currents to rectifiers 9, 10 and 11, respectively. The direct-current terminals of the rectifiers are connected in series and supply current to a local circuit consisting of battery 13 or any equivalent source of constant D. C. potential, the operating coil of the switch 14 and the resistance 12. The polarity of the battery 13 is opposed to that of the rectifiers 9, 10 and 11. Closure of the contacts 15 may effect the paralleling of the two branches of the distribution system directly or may close another local circuit including the operating coil of the paralleling switch.

In the embodiment of my invention described herein, the switch 14 serves as a control relay for the switch 16 which, when operated by the energization of its closing coil, connects the circuits 1—2 and 3—4 in parallel.

The operation of this relay system will now be described.

Assuming first that the voltages of the branches 1—2 and 3—4 are both normal and in phase, transformers 6 and 8 will have the voltages of the two branches impressed upon them, while transformer 7 will have no voltage across its terminals since it is subject to the resultant of the voltages of the two branches and, since, whenever the voltages of the two branches are equal and in phase, their resultant is zero. This follows from the fact that, since both branches are fed from the same generating source, the voltages thereof are always in synchronism. Because of the voltages induced in the secondaries of transformers 6 and 8, unidirectional voltages will appear across the direct-current terminals of rectifiers 9 and 11, and the sum of these voltages will be impressed upon the local circuit, including the switch 14, but will be opposed by the voltage of battery 13. The voltage of the battery 13 is adjusted to be larger than that from rectifiers 9 and 11 in series, so that with normal voltages on both branches of the alternating-current distribution system, the difference between the battery voltage and that of the rectifiers in series will be suffi-

cient to operate the switch 14 to cause the two branches of the system to be paralleled.

The function of resistance 12 is to permit current from battery 13 to energize the coil of switch 14 when the sum of the voltages of rectifiers 9, 10 and 11 is sufficiently small.

Now, if the voltage of one of the branches rises to a value above normal, while that of the other remains at its normal value, the voltage impressed upon the local circuit by the rectifiers will be sharply increased, because of the increase in the voltage of that particular branch, the voltage of which is above normal and also because of the resultant voltage impressed upon the transformer 7. This will result in a greater voltage upon the local circuit in opposition to that of the battery 13, and, therefore, operation of the switch 14 will be prevented, since the difference between the battery voltage and the sum of rectifier voltages is now insufficient to operate the switch.

If, however, the voltage of one branch decreases below normal, while the other remain normal, the voltage upon the local circuit will be just the same as it was when both were normal. This is due to the fact that, whenever the voltage of either branch decreases, although the voltage on the transformer connected to that branch also decreases, the voltage upon the transformer 7 is increased by just the same amount, thus causing conditions in the entire system to remain unchanged. As a result of these conditions, the switch 14 will be operated just as in the case where both branches of the distribution system had normal voltage thereon.

Another result of the above described scheme of operation is that it permits paralleling at wider phase angles between the voltages if one of them is below normal. This voltage-compensating action is more fully described in my copending application Serial No. 227,461, filed Oct. 20, 1927.

Operation of the switch 14 will be effected not only when the voltages of the two branches are both normal but also whenever these voltages are equal and below normal. This is apparent from the fact that, whenever the voltages of the two branches are equal, the transformer 7 has no voltage impressed upon it and, therefore, the rectifier 10 does not supply any direct-current voltage to the local circuit and, as previously stated, the direct-current voltages from the rectifiers 9 and 11 are not sufficient to prevent the switch 14 from being operated by the voltage of the battery 13, if the voltages are equal and below normal.

If the voltages of both branches, however, are above normal, the sum of the rectifier voltages will be increased sufficiently to prevent operation of switch 14 by the voltage of battery 13. This will be the case even should both the voltages increase by the same amount, so that transformer 7 and rectifier 10 would not be effective to add any direct cur-

rent voltage to oppose that of battery 13. If only one of the voltages increases above normal, however, the increase in the sum of the rectifier voltages will be greater than if both the branch voltages increased by the same amount, because of the added effect of transformer 7. As a result, switch 14 will not be energized when both voltages are above normal, whether equal or not.

If conductors 1-2 and 3-4 represent corresponding phase branches of a polyphase distribution system, the voltages on transformers 6 and 8 will be those of the corresponding phases, and the voltage on transformer 7 will be the resultant of the phase voltages, as explained above. Under these conditions, if, for any reason, either of the branches becomes unbalanced so that the neutral point shifts, paralleling will be prevented because of the fact that the direct current resulting from the phase voltages plus that from their resultant, prevents operation of the switch 14. Paralleling will take place only when the two branches of the system are balanced and when the voltages of the branches have the relations previously indicated, i. e., when the branch voltages are equal and normal or below or when the branch voltages are unequal but neither is above normal.

Various modifications in the system, and in the arrangement and location of parts may be made within the spirit and scope of my invention and such modifications are intended to be covered by the appended claims.

I claim as my invention:

1. A system for connecting a pair of alternating-current circuits comprising a magnetically operated circuit connector, a control relay therefor, a direct-current source for energizing said relay and means for setting up a voltage to oppose the energization of said relay in proportion to the voltages of said circuits and in proportion to the instantaneous resultant thereof, whereby said circuits will be connected whenever the voltage of one is below normal, and that of the other is normal and in phase with the voltage of the first mentioned circuit.

2. A system for connecting a pair of alternating-current circuits comprising a magnetically operated circuit closer, a control relay therefor, a direct-current source for energizing said relay, other direct-current sources in series opposition to said first-mentioned source for opposing the energization of said relay in proportion to the voltages of said circuits and the instantaneous resultant thereof, whereby said circuits will be connected at all times when the voltage of one is normal, and the other below normal or when both voltages are equal and not above normal, if said voltages are in phase.

3. A system for connecting alternating-current circuits comprising a connecting switch, a relay for controlling said switch, a

source of direct-current for energizing said relay, rectifiers connected across said circuits and a rectifier connected between said circuits, the output of said rectifiers being connected in series opposition to said direct-current source, whereby said relay is energized to close the connecting switch whenever the voltages of said circuits are equal, and not above normal and whenever one of the voltages is normal and the other less than normal, and whenever both voltages are below normal, regardless of their relative values, if the said voltages are in phase.

4. In a system for connecting a pair of alternating-current circuits when conditions therein are suitable, means for compensating for a decrease in the voltage of either circuit comprising a local circuit including means for producing a direct-current voltage proportional to the voltages of the circuits and proportional to the instantaneous resultant thereof, a source of constant opposing direct-current voltage, and the closing coil of a relay for controlling the connection of said circuits, the value of said opposing voltage being of sufficient magnitude to energize the said closing coil to the operative value whenever the voltage of one or both circuits is normal or below and in phase with that of the other circuit but insufficient to energize said closing coil if the voltage of either of said circuits is above normal.

5. A system for connecting alternating-current circuits comprising a circuit closer for connecting said circuits, a source of current having a predetermined voltage, controlling means for said circuit closer adapted to be energized from said source of current, and means for developing a voltage opposing the energization of said controlling means in proportion to the voltages of the circuits and their instantaneous resultant, whereby the said circuits will be connected whenever their voltages are normal and in phase or below normal and in phase.

45 6. In a system for connecting a pair of alternating-current circuits comprising a circuit closer for connecting said circuits, a source of current having a predetermined voltage, a relay for controlling said circuit closer and adapted to be energized from said source of current, and means for opposing the energization of said relay by a voltage that is proportional to the voltages of said circuits and in proportion to the instantaneous resultant thereof, whereby the circuits will be connected whenever the voltages are both below normal and in phase.

7. A system for connecting a pair of alternating-current circuits comprising a magnetically operated circuit-connector, a source of direct-current supply having a predetermined constant voltage, a control relay for said circuit connector adapted to be energized from said current source, and means

for developing a voltage to oppose the energization of said relay in proportion to the voltages of the circuits and their instantaneous resultant, whereby said circuits will be connected when the voltage of one is normal and that of the other subnormal and the voltages are in phase or when both are equal, not above normal and in phase.

In testimony whereof, I have hereunto subscribed my name this 12th day of September, 1927.

PHILLIPS THOMAS.
